UNITED STATES PATENT OFFICE.

FREDERICK A. EMERY, OF HAVERHILL, MASSACHUSETTS.

HEELING-MACHINE.

1,314,071.

Specification of Letters Patent. Patented Aug. 26, 1919.

Application filed November 4, 1915, Serial No. 59,530. Renewed January 6, 1919. Serial No. 269,970.

To all whom it may concern:

Be it known that I, FREDERICK A. EMERY, a citizen of the United States, residing at Haverhill, in the county of Essex and State 5 of Massachusetts, have invented an Improvement in Heeling-Machines, of which the following is a specification.

This invention relates to certain improvements in heeling machines, and more particularly to machines for attaching heels 10 which comprise a leather base-section, and a rubber top-section, through each of which the attaching-nails must be driven.

At the present time, the rubber top-sections are attached both by hand and by machine, and, while they may be attached by machine somewhat more rapidly than by hand, the machines which are, so far as I am aware, at present in use, for this purpose, require great physical exertion, on the part 15 of the operator, for the reason that the attaching-nails must be driven about $\frac{1}{8}$ of an inch below the level of the tread surface of the rubber heel section, and, to do this, the operator has to jack the heel, by means of the foot-treadle, against the nail plate with sufficient force to compress the rubber to a 20 considerable extent before the final pressure of the machine is applied thereto, so that the nails will be driven into the base-section to such an extent that, when the rubber expands the nails will be countersunk, to some extent, although, usually, not to the extent desired.

The object of my invention is to provide 25 a machine, of the above-described character, with means whereby the leather base-section may be easily and rapidly attached, and the attaching-nails of the rubber top-section may be driven and countersunk to the desired extent, and the whole operation may be 30 performed without greater difficulty or effort on the part of the operator than is necessary in attaching an ordinary leather heel and top-lift.

45 I accomplish this object by the means shown in the accompanying drawings, in which an embodiment of my invention is shown, and in which:—

Figure 1 is a front elevation of a well-known form of heeling-machine provided 50 with certain parts embodying my invention.

Fig. 2 is a sectional view thereof, on the line 2—2 of Fig. 1.

55 Fig. 3 is a top plan view, on an enlarged scale, of the nail plate carrier, showing the same in one of its extreme positions.

Fig. 4 is a view, similar to Fig. 3, showing the carrier in its other extreme position.

Fig. 5 is a sectional view, on the line 5—5 of Fig. 4. 60

Fig. 6 is a sectional view, on the line 6—6 of Fig. 3.

Figs. 7 and 8 are detail views partly in elevation and partly in section, illustrating different stages of the heeling operation. 65

Fig. 9 is a bottom plan view of the nail plate carrier.

Figs. 10 and 11 are sectional views, on an enlarged scale, taken at the lines 10—10 and 11—11, respectively, of Figs. 3 and 4. 70

Fig. 12 is a vertical section of the driver block, on an enlarged scale, taken at the line 2—2 of Fig. 1.

Fig. 13 is a detail plan view of one of the nail plates. 75

Fig. 14 is a detail bottom plan view of a blank-holding means which I preferably employ.

The main portion of the machine, to which I have shown my invention as applied, is of similar construction to the machine illustrated in the U. S. patent to Pope, #446,885, said machine comprising a main frame 10, having a main driving shaft 11, mounted therein, said shaft being arranged to reciprocate the cross-head 12, mounted on the vertical side rods 13. The jack 14 is mounted beneath the cross head upon an adjustable support 15, which is adapted to be raised by a treadle 16, 80 through intermediate mechanism, comprising a rack bar 17 arranged to rotate a gear 18, mounted on an elevating screw 19, on the upper end of which the support 15 is carried, so that the jack will be raised when 85 the treadle is depressed, and lowered when the pressure on the treadle is removed, a spring 9 being provided to lift the same, and to operate the parts actuated thereby in the opposite direction. The machine thus far 90 described is well known in the art, and is believed to require no further description.

According to my invention, a cross bar 8 is rigidly supported on the machine frame in such a position that the side rods 13 pass 105 through the ends thereof, and a bracket plate 20 is supported on said bar in a horizontally disposed position. A nail-plate-carrier 22 is provided, which comprises a flat, circular, metal casting, of suitable 110 thickness, rotatably mounted on and supported by a bolt 23, beneath the plate 20.

The rear side of the cross bar 8 is cut away to provide a segmental shaped recess, extending from top to bottom thereof, to receive the front portion of the carrier, as shown in Figs. 3 and 4. Adjustable stop bolts 24, 25, are provided on said carrier in position to engage the bar 8 and limit the movement of rotation thereof to 90° from either extreme position. Said carrier 22 is provided with two radially disposed nail-plate-receiving recesses opening from the edge thereof, and so arranged that their radial central lines are exactly 90° from each other, and nail plates 26, 27, are mounted in said recesses respectively, said plates being supported on suitable guide ribs 22', so that they may be readily removed and replaced by moving them radially in said recesses, any suitable means for locking them in position being provided. A driver block 28 is removably mounted on the under side of the cross head 12 and said nail plates 26, 27, are so arranged in the carrier 22 that one or the other will be held directly beneath said driver block in one or the other of the extreme positions of the carrier, shown in Figs. 3 and 4. Two distinct gangs of drivers 29 and 30, are mounted in said driver block, the driver gang 29 being shown as depending a short distance below the ends of the driver gang 30. The driver blocks 26, 27, are each provided with two sets of nail passages 29^a and 30^a (see Fig. 13), which correspond exactly in arrangement and size to the drivers of the two gangs 29 and 30, respectively, so that, when the cross head is lowered, said drivers will pass into and through the corresponding passages of the particular driver block which is at that time in position beneath the drivers.

With the above-described construction, when carrier 22 is in such a position that the nail plate 26 is held beneath the driver block 28, so that the drivers would pass through the nail passages of said plate, and is, therefore, in its nailing position, the other plate 27 will be held in a position 90° therefrom at the left side of the machine, while, when the plate 27 is held in its nailing position, the plate 26 will be in the directly opposite position at the right side of the machine. The bracket plate 20 is so formed that it does not extend beneath the driver block and is recessed from its edge directly over the two diametrically opposite positions of nail plates 26, 27, at the right and left of the machine, above referred to. Nail-sticking plates 31, 32, are removably mounted on the plate 20 directly over these recesses, the plate 31 having apertures 30^b therein, corresponding in position to the apertures 30^a in the nail plates 26, 27, and the plate 32 having apertures 29^b therein, corresponding in position to the apertures

29^a of said nail plates. Said plates 31 and 32 are also supported in such positions that the apertures thereof will register with the corresponding apertures of the nail plates when the latter are held thereunder. 70

The carrier 22 is provided with heel-holding means on its under side, in position to hold a heel blank directly beneath and against the under side of the nail-plates 26 and 27. The particular construction of 75 heel-holding means, which I preferably employ to hold the blank beneath the nail plate 27, is particularly shown in Figs. 5, 9, 10, and 14, and is mounted in a pair of parallel ribs 39 on the under side of the 80 carrier 22, said ribs having a pair of guide-ways formed in their adjacent sides, one over the other (see Fig. 10). A pair of parallel arms 38' are mounted to slide in the uppermost of said guide-ways, the outer 85 ends of said arms being connected by a heel-breast-engaging bar 38, and an intermediate portion thereof being connected by a cross-bar 42. A plate 37 having a V-shaped heel-receiving and centering recess in one end 90 thereof, is mounted to slide in the lowermost of said guide-ways, said plate being connected by parallel arms, or rods 37', to a cross plate 37'' to the rear end of which a depending rib 40 is secured, an adjusting 95 screw 41, having a swivel connection with the carrier 22, being threaded in said rib 40, whereby the position of said plate 37 may be adjusted. Said cross bar 42 and plate 27'' are connected by springs 43, which act 100 to draw the bar 38 toward the heel-receiving end of the plate 37. By this arrangement, the position of a heel-blank held between the bar 38 and plate 37 may be varied with 105 relation to the nail plate 27 without varying the force with which the springs 43 draw the bar 38 against a heel held in the recess of plate 37. The means for supporting a rubber top-section beneath the nail plate 26 comprises a rib 35 which is attached to the 110 under side of plate 26, and is formed to provide a concave recess, to correspond to the rear portion of the heel-blank, and a breast-engaging bar 36 which is mounted on dowels 35', in the rib 35, to move transversely 115 toward and from the recess of the latter, and springs 44 are arranged to draw said bar toward said plate, to clamp the blank therebetween. The carrier 22 has handles 45 thereon, so that it may be conveniently 120 rotated on its pivot 23.

To operate the machine to its greatest capacity, the operator employs two assistants, who stand at the right and left sides 125 of the machine, and stick the nails and place the heel blanks in the holder. The operator of the machine stands in front of the machine in the usual manner, and places the shoe on the jack, as indicated in Fig. 2. A blank α , for the heel base is placed between 130

the members 37 and 38, while they are in the position beneath the loading plate 31, and a nail is placed in each hole of the plate 31, so that it will pass into the corresponding 5 nail passages in the nail plate 27 and rest on the blank, as shown in Fig. 10.

The nail plate carrier 22 is then rotated through 90° , in the direction of the arrow in Fig. 3, carrying the nail plate 27, with 10 the heel blank supported therebeneath, into position over the jack and beneath the driver block. The operator then depresses the treadle 16 and lifts the jack, forcing the heel seat of the shoe thereon firmly 15 against the heel blank in the desired position of attachment, the position of the blank being adjusted, if necessary, by the screw 41, and then he operates the starting mechanism of the machine, so that the cross head 20 12 is caused to descend, and the driver gang 30 to enter the passages 30^a and engage the nails thereon, and drive them through the blank into the heel seat, in the ordinary way, so that the blank is attached thereto. The 25 relative arrangement is such that the drivers 30 are carried down to the level of the under side of the nail plate, so that the nails will be driven flush with the surface of the heel. The drivers 29 will, at the same time, pass 30 into and through the passages 29^a, and, as these drivers are somewhat longer than the drivers 30, their ends will be carried below the surface of the plate and be forced into the top portion of the heel blank, so that 35 they will prick a corresponding series of holes therein, to a depth corresponding to the distance which they project below the ends of the drivers 30, as shown in Figs. 5 and 7.

40 While the carrier is in the position to attach the heel base, shown in Fig. 4, the operator's assistant places a rubber top-section γ between the clamp members 35 and 36 and then sticks a nail into each hole 29^b 45 of the plate 32, so that these nails rest on said heel section, as shown in Fig. 11. As soon as the cross head is lifted, the carrier is then rotated in the opposite direction, as indicated by the arrow in Fig. 4, returning 50 it to the position of Fig. 3, and bringing the rubber top-section into position over the base-section which has just been attached. When the cross head moves up, the operator releases the treadle 16, so that the jack 55 is lowered, and, as soon as the top section is moved into position over the jack, he again depresses the treadle 16 and presses the heel base, which has just been attached, up against the under surface of the top section, and, while the parts are held in this 60 position, the machine is again operated, so that the cross head again descends, and causes the longer drivers 29 to engage the nails which have been placed in the nail 65 passages 29^a and to drive them into and

through the rubber heel and into the heel base, so that the rubber section will be attached thereto. As, in the previous operation, the base section has been pricked to some extent by the longer drivers 29, these 70 prick holes will assist in the proper guidance of the attaching nails of the top-section, when they emerge from the latter and pass into the heel base, said prick holes being, obviously, in exact alinement with 75 the direction in which these nails are driven, and between the nails which have been driven into the heel base, so that the attaching nails of the top section will not encounter those of the base-section. 80

As has been stated, it is necessary that the attaching nails of the rubber top section be countersunk to the depth of about $\frac{1}{8}$ of an inch the extent to which the drivers 29 extend below the surface of the nail plate, 85 when the cross head is in its lowest position, is made to correspond to this distance, so that the nails, driven thereby, will be driven below the tread face of the top section to a corresponding extent, as shown in Figs. 6 90 and 8. As the drivers 30 are not moved below a point where their ends are flush with the surface of the nail plate, it follows that, while the longer drivers 29 will drive the nails below the tread face of the rubber 95 top, the drivers 30 only will touch its surface, and will not penetrate the same, so as to cause injury thereto.

The cross head then ascends again, and, as the attaching operation is then finished, 100 the shoe may be removed, and the operation repeated. The operation of attaching the leather heel base and rubber top section may thus be rapidly and effectively performed, the operation being as rapid and easy for 105 the operator as the ordinary operation of attaching the ordinary heel and top lift.

The above described devices, constituting an embodiment of my invention, may be easily applied to the well-known commercial machine above referred to, without modification, other than the substitution of these devices for certain other devices with which such machines are usually provided. 110

It will be obvious that the nail plates, nail-sticking plates, and driver blocks, will be changed according to required conditions, and that, while the rotatably mounted nail-plate carrier is more desirable than any 115 other construction of which I am aware, it is not essential to the generic principles of my invention. Also, that, while I prefer to have the carrier rotated through about $\frac{1}{4}$ of a revolution in each direction, so that two 120 operator's assistants may be employed to advantage, and the arc, through which the carrier is oscillated, may be as short as practicable, thereby enabling the volume of work performed to be increased to the great- 125 130

est extent, practicable, yet if a single assistant is to be employed, it would be quite as desirable to have the carrier moved as near to $\frac{1}{2}$ a revolution as would be possible, without having the two sets of nail-sticking passages interfere with each other, and have the assistant stationed in the rear of the machine to which position the nail plates would then be carried for loading.

10 It will also be understood that automatic nail-loading means may be employed for each of the nail plates, instead of having the nails inserted by hand.

By having both gangs of drivers on one block and both nail plates provided with nail passages for each gang, the speed of the machine is considerably increased over an arrangement in which the driver gangs would be mounted in separate driver blocks on a 20 turret, carried by the head, and successively brought into position over the jack, in the well-known manner in which separate gangs of awls and drivers have been previously employed; for the reason that the time required to change the turret after each nailing operation would cause additional delay. It will be understood, however, that my invention is not limited to the arrangement of both driver gangs on the same head, but that 25 this is a greatly preferred and highly advantageous construction, not only for the reason that the speed of the machine is increased, but also because the advantage due to the pricking of the base section to receive 30 the top section nails. It will be further apparent that it would be possible to employ only one nail plate in attaching both base and top sections of the heel, by first placing the base-section-blank in position beneath 35 the nail plate, and driving the attaching 40 nails from one set of nail passages and then placing the top-section-blank in position beneath the same nail plate, and driving the attaching nails therefor from the other set 45 of nail passages. While this operation would be substantially slower than that already described, as the preferred method of operation, yet the advantage of having one set of drivers longer than the other set, so 50 that the base section would be pricked and the top section attaching nails would be countersunk, would still be secured.

I claim:—

1. A heelng-machine comprising a nail-plate having two sets of passages there-through, one arranged for the attaching nails of a base heel-section and the other for the nails of a top-heel-section, and a head having two gangs of drivers thereon, arranged to be passed through the corresponding passages of said plate, the driver gang for the top section passages being arranged to extend beyond the engaging face of the nail-plate, and the driver gang for the base-section to extend approximately flush with

said face, at the ends of their respective nail-driving operations.

2. A heelng-machine comprising a nail-plate having two sets of passages there-through, one arranged for the attaching 70 nails of a base heel-section and the other for the nails of a top-heel-section, and a driver block having two gangs of drivers extending from the face thereof and arranged to be passed through the corresponding passages 75 of said plate, the drivers of the gang for the top-heel-section passages being extended to a greater distance from said face than the drivers of the other gang, to prick the base-heel-section when the base heel-section is attached, and to countersink the nails in the top-heel section, when the top-heel-section is attached, without having the said drivers of the other gang penetrate the latter.

3. A heelng machine comprising two nail plates each having a double series of identically arranged driver passages, a driver block having a double series of correspondingly arranged drivers, means to move said nail plates successively into nailing position 85 beneath said drivers, and means to move said drivers through said passages when said plates are held in said nailing position.

4. A heelng machine comprising two nail plates, means to move said plates successively into nailing position, one plate having a set of passages for the attaching nails of a base heel-section and the other having a set of differently arranged passages for a top heel-section, and a head having two gangs 95 of drivers thereon, arranged to be passed through the passages of said plates, respectively, when in nailing position, to drive the nails into the corresponding heel-sections, the gang of drivers for driving the nails 100 of the top section extending beyond the points to which those of the other gang extend, at the end of the driving movement.

5. A heelng machine comprising two nail plates, one having a set of passages for the 110 attaching nails of a base heel-section and the other a differently arranged set for those of a top heel-section, means to move said nail plates into nailing position, successively, and a movable head having two gangs of drivers 115 thereon arranged to be passed thereby through the passages of said plates, respectively, when such plate is in nailing position, one gang of drivers being arranged to extend flush with the heel-engaging face 120 of the nail plate, at the end of the driving movement, and the other gang being arranged to extend beyond said face, to drive the nails below the surface of the top section.

6. A heelng machine comprising a pair of nail plates, each movable to and from a nailing position, and each having a set of passages for the drivers for the attaching 125 nails of a base section, and a differently ar- 130

- ranged set for the drivers for the nails of a top section of a heel, a driver block having two gangs of drivers thereon arranged to pass simultaneously through both sets of 5 passages, of either nail-plate, when in nailing position, and means to move said driver block to drive a group of nails through one set of passages in one plate and then through the other set of passages in the other plate, 10 to attach said sections successively.
7. A heelng machine comprising a pair of nail plates successively movable to nailing position, each having a set of passages for the drivers for the attaching-nails of a 15 base section and a set for the drivers for the nails of a top section of a heel, a driver block having two gangs of drivers thereon arranged to pass simultaneously through all of said passages in either plate, and means 20 to move said driver block to drive a group of nails through one set of passages in one plate and then through the other set of passages in the other plate, to attach said sections successively, the gang of drivers for 25 driving the nails for attaching the top section being arranged to extend to greater distances from the block than the drivers of the other gang.
8. A heelng machine comprising a pair 30 of nail plates, each having two sets of driver passages therethrough, a carrier in which said nail plates are mounted, said carrier being movable to carry said nail-plates to nailing position, successively, a 35 driver block, two gangs of drivers thereon arranged to be passed through the passages of each plate, when in nailing position, and means to direct a group of nails into one set of passages of one nail plate and into the 40 other set of passages of the other plate.
9. A heelng machine comprising a pair of nail plates, one having a set of passages therethrough for the attaching nails of a base heel-section and the other having a 45 differently arranged set of passages for the nails of a top heel-section, a carrier on which said nail plates are mounted, said carrier being movable to hold said nail plates one in heelng position and the other in a loading position, successively, two gangs of drivers, 50 one adapted and arranged to pass through one of said sets of passages and the other through the other set of passages, when the corresponding nail plate is in heelng position, the drivers for the top heel-section 55 nails being arranged to extend beyond the level of the ends of the other drivers, to force the nails below the tread face of such section, and means to operate said drivers 60 to drive the nails of the different sections, successively.
10. A heelng machine comprising a pair of nail plates, one having a set of passages therethrough for the attaching nails of a 65 base heel-section and the other having a 70 differently arranged set of passages for the nails of a top heel section, a carrier on which said nail plates are mounted, said carrier being movable between a position to hold one of said nail plates in one loading position and the other in a heelng position, and a position to hold the former in said heelng position and the latter in another loading position, nail-guiding means in each of said loading positions having passages arranged to direct the nails into the respective 75 passages of said nail plates when in their respective loading positions, and two gangs of drivers, one adapted and arranged to pass through one of said sets of passages and the other through the other set of passages, successively, when the corresponding nail plate is in heelng position.
11. A heelng machine comprising a jack, a head having two gangs of drivers thereon, 80 a carrier having a heel top-section nail-plate and a heel base-section nail plate mounted thereon, and oppositely movable between two positions, in one of which it holds the top-section plate in heelng position between 85 the jack and head, and the base-section plate in a loading position at one side of said heelng position, and in the other of which it holds the base-section plate in said heelng position and the top-section plate in a loading 90 position at the opposite side of said heelng position, said nail plates having nail passages therethrough respectively corresponding to said driver gangs, nail-guiding means in each of said loading positions for 95 guiding the nails into their corresponding passages, and means to operate said drivers, to drive the attaching nails from said plates successively.
12. A heelng machine comprising a vertically movable head having two gangs of drivers thereon, a pair of nail plates, one having a set of passages for one of said gangs of drivers, and the other a set of 100 passages for the other gang, and a carrier for 105 said nail-plates mounted to oscillate about a vertically disposed axis, to hold said nail-plates successively in nailing position, and at the same time, to hold one and then the other in oppositely disposed loading positions, at opposite sides of said nailing position.
13. A heelng machine comprising a vertically movable head having two gangs of drivers thereon, a pair of nail-plates having 110 nail-passages therethrough, respectively corresponding to said driver gangs, a carrier for said nail-plates horizontally movable in opposite directions alternately to hold said nail-plates, one in a loading position, and 115 the other in a nailing position, and means to operate said head to force the driver gangs through the corresponding passages of said nail-plates successive.
14. A heelng machine comprising a ver- 120
15. A heelng machine comprising a carrier having two sets of nail-passages, respectively corresponding to two gangs of drivers, a carrier for said nail-passages horizontally movable in opposite directions alternately to hold said nail-passages, one in a loading position, and the other in a nailing position, and means to operate said carrier to force the driver gangs through the corresponding passages of said nail-passages successive.
16. A heelng machine comprising a carrier having two sets of nail-passages, respectively corresponding to two gangs of drivers, a carrier for said nail-passages horizontally movable in opposite directions alternately to hold said nail-passages, one in a loading position, and the other in a nailing position, and means to operate said carrier to force the driver gangs through the corresponding passages of said nail-passages successive.
